(57) **CLAIM**

The ornamental design of a barbecue grill, as shown and described.

DESCRIPTION

FIG. 1 is a front perspective view of a barbecue grill;
FIG. 2 is a right-side elevational view wherein the left-side elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a barbecue grill is for the purpose of illustrating environmental structure and forms no part of the claimed design.
